UNITED STATES PATENT OFFICE.

HARVEY C. MARKMAN, OF DENVER, COLORADO.

GAME APPARATUS.

Application filed November 19, 1927. Serial No. 234,396.

The present invention is concerned with the provision of a game apparatus of an entertaining and instructing nature.

The primary object of the invention is to 5 provide a game apparatus with which the progress and development of civilization may be traced, and many of the causes of the advance and retardation of civilization noted.

10 More specifically the game apparatus includes a game board over which are movable at chance determined intervals, two token members. One of the token members is adapted to represent the mass of humanity, 15 while the other token member represents the idealism which has been responsible for the development of civilization. The object of the game is to so move the token members that they are brought into a predetermined 20 relative position.

The means which are utilized for controlling the movement of the token members are preferably cards. These cards bear symbols which indicate the direction of movement of the tokens. They also bear quotations relating to associated legends on the tokens, such quotations and legends being directly related to certain causes of the advance or retardation of progress.

25 30 The invention may be more fully understood from the following description in connection with the accompanying drawings wherein—

Fig. 1 is a perspective view of the game 35 board used in the apparatus, the two token members being indicated in dotted lines.

Fig. 2 is a sectional detail through the game board on the line 2—2 of Fig. 1.

Fig. 3 is a transverse sectional view on 40 the line 3—3 of Fig. 2.

Fig. 4 is a plan view of one of the token members.

Fig. 5 is a sectional view on the line 5—5 of Fig. 4.

45 Fig. 6 is a plan view of the other token member.

Fig. 7 is a longitudinal sectional view therethrough on the line 7—7 of Fig. 6.

Fig. 8 is a collective view illustrating several of the cards which bear a common identifying character.

50 55 The game board is in the nature of a flat plate 10 preferably of rectangular shape and provided with a raised rim 11 which encircles the playing field. A longitudinally extending groove 12 extends along the

median line of the game board and is provided at intervals with pockets or depressions 13, these depressions being preferably numbered as best seen in Fig. 1. One of the 60 raised margins of the board is provided with a series of equidistantly spaced numbered notches 14, these notches being preferably aligned with the pockets 13, but so arranged that the numbers on the pockets are higher 65 than the numbers in the opposite notch, preferably two numbers higher for a purpose which will be later described.

One of the token members illustrated in Figs. 6 and 7 consists of a plate or card 15, 70 which, for symbolic reasons with which the present invention is not concerned, is egg shaped. The token 15 represents the mass of humanity, bears the legend "Humanity" on its face, and at its pointed end bears 75 other legends such as the words Interest, Training and Cooperation, which legends relate directly to certain causes for the advance of humanity.

The other token member 16 illustrated in 80 Figs. 4 and 5 is preferably of star shape, each point of the star being numbered and each bearing legends. Preferably two legends are printed on each star point, these legends relating to, or being suggestive of 85 certain human activities to which the progress of civilization is more or less directly attributable. The grouping of the legends is to avoid an undue number of star points by using a single point to display more or less related legends such as the words Education and Science, Exploration and Conquest, etc.

The token 15 is provided with a handle member 17, the lower end 18 of which is 90 pointed and adapted to seat in any one of the pockets 13 along the groove 12. The token member 16 is provided with a similar handle 17, the pointed end 18 of which is also adapted to be accommodated in the pockets 100 13. In playing the game, the egg shaped token 15 is movable backward and forward along the groove 12 at intervals determined by the symbols on a pack of cards. The token 16 is not only shiftable along the 105 groove 12, but is adapted for a rotary movement to dispose any one of its pointed ends in an associated notch 14; the cards which are used in playing the game determine both the rotational movement and bodily 110 movement of the token 16.

The cards, of which there may be any de-

sired number in a deck, are subdivided into three general classes which I have elected to distinguish by the following names. A group of cards bearing the legend "Leaders" 5 are used to control the bodily movement of the star. A second group bearing the legend "Ideals" are used to control the rotation of the star; while a third group designated as "Positive" and "Negative" are used 10 to control the backward and forward movement of the egg.

Preferably, these three classes are distinguished not only by the legend which they bear, but by colors. I have shown for illustrative purposes, the "Leader" cards as red, 15 the "Ideals" as blue, and the "Positive" and "Negative" cards as white. In practice all of the cards are preferably white, and the legends and other indicia thereon being 20 printed in distinguishing colors. For instance, the "Leader" cards are printed in red ink, the "Ideal" cards in blue ink, and the "Positive" and "Negative" cards in black ink. All three types of cards bear numerals 25 in their corners which correspond to one of the numerals appearing on the points of the star.

I have illustrated in Fig. 8 one of the "Leader" cards, one of the "Ideal" cards, one 30 "Positive" card and one "Negative" card. All of these cards bear quotations relating in some manner to the general classifications of the cards, and to the legend appearing on the star token.

35 Any attempt to fully elucidate the symbolism of the tokens, the token legends, the card legends or the card quotations, would involve an unduly lengthy discussion of matters not properly pertinent to the invention, and such a discussion is therefore dispensed with in the present application.

The method of playing the game is subject to an infinite variety of variations; it will be quite obvious for instance that the apparatus 45 in addition to being used for controlling token movements over the board, might be utilized for suggesting conversational topics and for promoting general discussions on various phases of the development of civilization. For illustrative purposes however, I shall merely describe one extremely simple manner in which the game may be played.

Rules: The egg is placed in the extreme left hand position on the board with its small end toward the star, the latter being located three positions ahead with the point numbered "One" in the receiving notch 50 on the frame.

60 The pieces are manipulated by lifting them slightly out of the pockets and either sliding them along the groove into the next pocket, or in the case of the star, rotating it to bring the proper point into the notch.

65 The cards are shuffled and one card is dealt to the first player on the dealer's left.

If the cards bear a "Positive" quotation, the egg is moved forward one position toward the star. If the card bears a "Negative" quotation, the egg is moved one position away from the star. If the card bears an "Ideal" 70 quotation, the star is rotated, so that the numbered star point corresponding to the number on the "Ideal" card is brought to rest in the notch at the top of the board. This uppermost star point may be regarded 75 as indicating a dominant ideal or motive of civilization at that particular stage of the game.

If the card bears a "Leader" quotation, the star is moved one position away from the 80 egg, and in addition turned to the position indicated by the index number of the card. The game is won at any time when the egg and star are in adjacent positions by the first player to draw either a "Positive", "Ideal" 85 or "Leader" card bearing an index number identical with the number of the dominant ideal as revealed by the position of the star, or by the player who moves the egg into the adjacent position when the index number of the card which causes that move corresponds to the number of the dominant ideal. 90

95 Any desired system of scoring may be utilized; the score of the one who completes the game being based upon the values of the dominant ideal at that time. Preferably, the cards held by all players at that time are also scored to the credit of the player holding them.

100 After each player has had an opportunity to play a card, another card is dealt all around, and the play proceeds.

Obviously, various changes and alterations might be made in the general form and arrangement of the parts described without departing from the invention. Hence I do not wish to limit myself to the details set forth, but shall consider myself at liberty to make such changes and alterations are fairly 105 fall within the spirit and scope of the appended claims. 110

I claim:

1. A game apparatus including a game board, tokens bodily movable in chance determined directions over the game board, one of said tokens being rotatable on its axis at chance determined intervals, and means for controlling the movements of the tokens. 115

2. A game apparatus including a game board, tokens bodily movable in chance determined directions over the game board, one of said tokens being rotatable on its axis at chance determined intervals, and means for controlling the movements of the tokens, 120 said means comprising a deck of cards. 125

3. A game apparatus including a game board, tokens bodily movable in chance determined directions over the game board, one of said tokens being rotatable on its axis at chance determined intervals, and 130

means for controlling the movements of the tokens, said means comprising a deck of cards including sets of cards indicative of the direction of bodily token movement and 5 sets of cards indicative of the extent of rotation of the rotatable token.

4. A game apparatus including a game board, tokens bodily movable in chance determined directions over the game board, one 10 of said tokens being rotatable on its axis at chance determined intervals, and means for controlling the movements of the tokens, the board being grooved and having spaced pockets in the groove, the token members 15 including portions to slide in the groove and seat in the pockets.

5. A game apparatus including a game board, tokens bodily movable in chance determined directions over the game board, 20 one of said tokens being rotatable on its axis at chance determined intervals, and means for controlling the movements of the tokens, the board being grooved and having spaced pockets in the groove, the token members 25 including portions to slide in the groove and seat in the pockets, the board also being formed with means to coact with the rotatable token.

6. A game apparatus including a game 30 board, tokens bodily movable in chance determined directions over the game board, one of said tokens being rotatable on its axis at chance determined intervals, and means for controlling the movements of the tokens, the 35 board being grooved and having spaced pockets in the groove, the token members including portions to slide in the groove and seat in the pockets, the board also being formed with means to coact with the rotatable token, said means comprising a row of 40 notches adjacent one edge of the board, the rotatable token being star-shaped so that one of its points may engage in one of said notches.

45 7. A game apparatus including a game board, tokens bodily movable in chance determined directions over the game board, one of said tokens being rotatable on its axis at chance determined intervals, and 50 means for controlling the movements of the tokens, said means comprising a deck of

cards including sets of cards indicative of the direction of bodily token movement and sets of cards indicative of the extent of rotation of the rotatable token, the rotatable 55 token including radial extensions, said extensions and said cards having similar identifying characters.

8. A game apparatus including a game board, tokens bodily movable in chance determined directions over the game board, one of said tokens being rotatable on its axis, 60 at chance determined intervals, and means for controlling the movements of the tokens, said means comprising a deck of cards including sets of cards indicative of the direction of bodily token movement and sets of cards indicative of the extent of rotation of the rotatable token, the rotatable token including radial extensions, said extensions 65 and said cards having similar identifying characters, and the board including means to coact with said radial extensions.

9. In combination with a game board, a token bodily movable and rotatable about its 70 axis at chance-determined intervals.

10. In combination with a game board, a token bodily movable and rotatable about its axis, said bodily movement and said rotation being independently controllable at 80 chance-determined intervals.

11. In combination with a game board, a pair of chance-controlled longitudinally movable tokens, one of said tokens being 85 rotatable at chance-controlled intervals.

12. In combination with a game board, a longitudinally movable token, a second longitudinally movable token rotatable about its axis, and chance-controlled means for governing the movement of said tokens. 90

13. In combination with a game board and a longitudinally movable token, a second longitudinally movable token rotatable about its axis, and chance-controlled means operating independently to control the longitudinal movement and the rotation of said tokens. 95

Signed at Denver, in the county of Denver and State of Colorado this 15th day of November, A. D. 1927.
